UNITED STATES PATENT OFFICE.

HEYE J. WESSELS, OF GERMAN VALLEY, ILLINOIS.

FENCE-POST, &c.

940,996.

Specification of Letters Patent. Patented Nov. 23, 1909.

Application filed May 6, 1908. Serial No. 431,291.

To all whom it may concern:

Be it known that I, HEYE J. WESSELS, a citizen of the United States, residing at German Valley, in the county of Stephenson 5 and State of Illinois, have invented a new and useful Improvement in Fence-Posts; and I do hereby declare the following to be a full, clear, and exact description of the invention, such as will enable others skilled 10 in the art to which it pertains to make and use the same.

This invention relates to fence posts and has special reference to an improved form of reinforced concrete fence posts.

15 One object of the invention is to provide an improved general construction for fence posts of this character.

Another object of the invention is to provide an improved reinforcing means for 20 such a fence post.

A third object of the invention is to provide a casing for such a fence post which is held in position in a novel manner.

A fourth object of the invention is to provide 25 a fence post with a broadened underground portion to which the top of a post is attached by the improved reinforcing means.

A fifth object of the invention is to provide 30 a casing for the upper part of the underground portion of such a post, said casing having an improved connection with the casing of the upper part of the post.

With the above objects in view the invention 35 consists in general of a fence post having a broadened base, the post and base being made of concrete reinforced and cased in a novel manner.

The invention further consists in certain 40 novel details of construction and combinations of parts hereinafter fully described, illustrated in the accompanying drawings, and specifically set forth in the claims.

In the accompanying drawings, like characters of reference indicate like parts in the several views, and:—Figure 1 is a side elevation of a fence post constructed in accordance with this invention. Fig. 2 is a longitudinal median section therethrough. Fig. 5 3 is a transverse section on the line 3—3 of Fig. 1. Fig. 4 is a similar section on the line 4—4 of Fig. 1.

The numeral 10 indicates the top of a post and this is formed of concrete or cement prepared in the usual manner. Surrounding

this top portion is a casing 11 provided with a plurality of openings 12 disposed in a vertical series. This portion of the post is preferably frusto-conical in form and the casing 11 extends over the top of the cement being 60 provided with a centrally disposed aperture 13. The post is provided further with a base 14 of relatively large cross sectional area and upon the upper end of this base portion is a protecting collar 15. The casing 11 extends downward into the base and at its lower extremity is formed with alternately arranged rebent members 16 which are riveted or otherwise secured to the casing 15 as indicated at 17, and downward 65 and inwardly extending members 18. These members are formed by longitudinally slitting the casing 11 for some distance above its bottom.

For the purpose of reinforcing the post 75 and holding the parts together as well as for the adjustment of fence wires there is provided a reinforcing element which comprises a portion 19 extending throughout the length of the post and terminating at a point 80 adjacent the bottom of the base 14 in a hook 20. The portion 19 is twisted as at 21 to form an eye and this eye projects through the opening 13. The reinforcing bar then extends downward adjacent the portions of 85 the casing, being provided with eyes 22 each formed by twisting a portion of the bar and these eyes project laterally through the openings.

In constructing the post the casing and 90 reinforcing wires are placed in a mold with the lower ends of the casing extending downward. The mold is then filled with concrete in the usual manner, the concrete being tamped from time to time as the filling goes on. When the mold has been filled the concrete is allowed to settle when the post may be removed by placing in the position in which it is to be used.

There has thus been provided a simple 100 and efficient device of the character described and for the purpose specified.

It is obvious that minor changes may be made in the form and proportions of this invention without departing from the material principles thereof. It is not therefore desired to confine the invention to the exact form herein shown and described, but it is wished to include all such as properly come within the scope of the appended claims.

105

110

Having thus described the invention, what is claimed as new, is:—

1. In a fence post, the combination with a concrete core and a larger concrete base, of a casing surrounding said core, said casing being provided with a portion having longitudinal slits therein to hold in the base, the segments formed by the slit portions being outwardly rebent and inwardly bent, and a second casing surrounding the top of the base and connected to the rebent portions of the first mentioned casing.
2. In a fence post, the combination with a concrete core, and an enlarged concrete base, of a casing surrounding said core, a second casing surrounding the base, means to connect said casing, comprising a head and outwardly rebent end portions formed on the first mentioned casing and a reinforcing rod extending upward from said base through the base and core, said rod being double on

its upper end and twisted to form a loop and hence extending downward again to the base.

3. In a fence post, the combination with a concrete core and an enlarged base, of a casing surrounding said core provided with a plurality of openings arranged in vertical series, a second casing surrounding said base, means to connect the first and second casing, comprising tongues formed at the lower end of the casing outward and upwardly bent and riveted to the base casing and a reinforcing rod provided with a series of twisted loops each projecting through one of the openings in the upper casing to form a fence wire attaching means.

HEYE J. WESSELS.
